MILKING MACHINE LINE HOLDER

George W. Wilhite, Rte. 1, Kuna, Idaho 83634

Filed Mar. 2, 1970, Ser. No. 21,688

Term of patent 14 years

Int. Cl. D15—99; D6—99

U.S. Cl. D98—1

FIG. 1 is a right front perspective view of the milking machine line holder embodying my new design as viewed from the bottom with the clamp exploded;

FIG. 2 is a left rear perspective view thereof with the rear portion of the clamp omitted for illustrative purposes;

FIG. 3 is a right front perspective view of the milking machine line holder in an alternate position, the milking machine shown in dotted lines for illustrative purposes only.

I claim:

The ornamental design for a milking machine line holder, substantially as shown and described.
